ARCH SUPPORT FITTER

Charles A. Hanington, Freeport, N. Y., assignor to The Scholl Mfg. Co., Inc., Chicago, Ill., a corporation of New York

Application November 3, 1955, Serial No. 544,648

7 Claims. (Cl. 12—1)

This invention relates generally to a device for fitting an arch support to the individual requirements of a foot of a person.

More specifically this invention relates to an arch support fitter device having novel means thereon capable of evenly applying pressure to an arch support mounted thereon to selectively vary the configuration of the arch support so that when the support is engaged with the plantar surface of the foot between the heel and ball of the foot, the support will evenly touch all points of the longitudinal arch.

Foot specialists today commonly utilize a leather hammer to reform the arch support to the particular foot specification. It is the purpose of the instant invention to provide novel means for more accurately and uniformly applying force to a given area on the arch support.

Accordingly, it is an object of the instant invention to provide a new and improved device capable of reforming an arch support.

Another object of this invention is to provide an arch support fitter with novel means capable of reforming an arch support which means may be reset in a large number of different positions thereby enabling a wide selective range of adjustments in reforming an arch support to a given specification.

A further object of this invention is to provide an arch fitter which lends itself to economical production.

Yet another object of this invention is to provide a novel method of reforming an arch support to individual specification.

A feature of this invention relates to my novel screw mechanism being mounted on one of two spaced blocks having the arch support securely maintained therebetween and with the screw mechanism being capable of both vertical and horizontal adjustment through a wide range of different positions.

A further feature of this invention is to provide my novel arch fitter with a screw actuated lever arm having an enlarged head for applying forces against an arch support to reform same according to specification.

While some of the more salient features, characteristics and advantages of the instant invention have been above pointed out, others will become apparent from the following disclosures taken in conjunction with the accompanying drawing, in which:

Figure 1 is an elevational view with parts broken away showing my novel arch support fitter;

Figure 2 is a plan view of the arch support fitter shown in Figure 1 having an arch support mounted therein;

Figure 3 is an enlarged fragmentary side elevation showing one of the selective positions in which the enlarged head is engaged with the arch support; and

Figure 4 is a bottom plan view of an arch support.

As shown on the drawings:

The reference numeral 9 indicates generally my novel arch support fitter which is capable of receiving therein a laminated arch support 10 of the type shown in Figure 4

2

which has a layer of metal 10a and a layer of protective covering material 10b.

It will be appreciated that in order to have proper fitting of an arch support to the longitudinal arch between the heel and the ball portions of a foot, arch portion 11 of the support must evenly engage against the plantar surface of the foot. To this end my novel arch support fitter 9 is adapted to selectively reform predetermined portions of the arch support 10.

10 My novel arch support fitter includes a base 12 having mounted thereon a stationary housing or shell 13 with one end open and the other end closed. The open end of the housing or shell 13 is adapted to receive one end of a longitudinally movable member 14 which is supported by base 12. The relative longitudinal movement is affected by reason of a screw mechanism 15 supported at one end by the housing 13 and at the other end by a block 16 carried by the shell 13.

The screw mechanism 15 includes a longitudinally movable screw 17 which extends through housing 13 and has a manually operable adjustment handle 18 at one end on the exterior of the housing 13. Intermediately carried upon screw 17 is member 19 having a headed portion 20 engaged in a seat 21 in member 14. Hence, upon manipulation of handle 18, member 14 may be actuated longitudinally relative to base 12.

Carried upon the movable member 14 is a second block 22 made of any suitable sturdy material which has an upper surface 23 slightly below the corresponding surface 30 upon block or anvil 16 for purposes hereinafter discussed.

One end of the block 22 is channeled at 24 to receive therein a tubular rod 25. The rod 25 may be slid up and down in channel 24 and maintained in a given position through adjustment of a set screw 26.

35 Carried upon the upper end of tubular rod 25 is a trunnion 27 which in turn carries my novel screw mechanism 28. Screw mechanism 28 has a threaded rod 29 with a handle 30 at one end and an enlarged forming head 31 at the other end which may be made or covered with raw hide or other similar material if desired. Upon turning of handle 30 the rod or shaft 29 is progressively moved through a tubular support 32 carried upon trunnion 27. The forming head 31 (Figure 3) is attached to the shaft 29 by means of a split compression ring 33 which is housed within a recess 34 in the head 31. It will be noted that the terminal 35 of shaft 29 is enlarged to provide an annular abutment which the ring 33 bears against.

50 My novel method may be practiced by initially placing an arch support 10 between the confronting blocks 16 and 22 with the portion to be deformed and worked upon remaining exposed so that the forming head 31 may be levered thereagainst. The remainder of the arch support 10 is adapted to be nested within contoured portion 36 thereby allowing the blocks 16 and 22 to be clamped together without damaging or otherwise bending the arch support 10.

55 Rod 25 is then adjusted by means of set screw 26 to a selected position so that the best possible angle may be secured in applying force or pressure upon the arch support 10. The handle 30 of screw mechanism 28 is then manipulated until forming head 31 is loosely engaged against the surface to be deformed. It will be noted that surface 23 of block 22 is below the corresponding surface of block 16 to permit free movement of the head.

60 Then upon further manipulation of handle 30 the head is forceably urged against the selected portion of the arch support which is ordinarily the longitudinal arch until the portion is reformed to individual specification. In so doing, the shaft 29 rotates while the head 31 (Figure 3) remains stationary by virtue of the pivotal connection between the head 31 and the rod 29. This minimizes maring of the arch support since the head 31 is sustained

in substantially non-rotating relation to the surface being reformed. In the case of stationary head 31 in Figures 1 and 2, by covering the head with leather, scratching of the arch support may be kept to a minimum.

It will be appreciated that pressure may be applied upon the portion to be reformed at various selective points by resetting and varying the several adjustments provided for this end.

In the forming operation the anvil or block 16 and more particularly the portion of anvil 16 which is elevated above surfaces 23 of block 22 serves as a back-up which aids in the reformation of the arch support.

It will be understood that modifications and variations may be effected without departing from the scope of the novel concepts of the present invention.

I claim as my invention:

1. In an arch support customizer, a releasable vise including vise portions for clamping and holding an arch support, a force applicator mounted on one of said vise portions and having an extendible extension pivotally mounted at an inclining angle relative to said vise for customizing and reforming selective portions of an arch support, and releasable means connected to said extension for moving the extension to vary the inclined angle between the extension and the vise.

2. In an arch support customizer, a releasable vise including vise portions for clamping and holding an arch support, the arch support customizer having a force applicator including an extendible extension pivotally mounted at an inclined angle relative to said vise for customizing and reforming selective portions of an arch support, and a forming terminal pivotally mounted on said extension to enable the terminal to be maintained stationary thereon against the arch support as the arch support is deformed without marring the surface of the support.

3. In an arch support customizer, a releasable vise including vise portions for clamping and holding an arch support with one of the portions having a hollowed out area and an elevated portion, a force applicator carried on said base and having an extendible extension pivotally mounted and extending at an inclined angle toward the elevated portion to facilitate in the customizing and reforming of selective portions of an arch support with the arch support held between the vise portions in the hollowed out area, said elevated portion providing a back up for the arch support to facilitate in the reformation thereof.

4. An arch support customizer for reforming at least a portion of an arch support comprising, a base, a clamp

on said base for supporting an arch support, a vertically extending rod carried by said base, a trunnion carried on said rod, and a screw mechanism carried by said trunnion and having a forming head on said mechanism which may be projected against selective exposed portions of an arch support to reform same to specification.

5. An arch support customizer for reforming at least a portion of an arch support comprising, a base, a vise on said base for supporting therebetween an arch support, and a screw mechanism carried by and extending at an inclined angle to said base, said mechanism including a shaft, a manually operable handle on one end of said shaft, a pivotally mounted forming head having a recess to receive an end of said shaft, and a compression ring housed within said recess to maintain said shaft and head in unitary relation whereby said head may be progressively projected against exposed portions of an arch support to reform to specification by manipulating said handle.

6. An arch support fitter device for reforming at least a portion of an arch support comprising, a base, arch support holding means on said base having portions movable relative to one another for supporting therebetween an arch support leaving a portion thereof exposed, and manually operable means positioned above and extending at an inclined angle relative to said arch support holding means for exerting a force against an exposed portion of an arch support to reform same to specification, one of said portions extending vertically above the other portion to provide a back-up against which the force exerted by the manually operable means is projected against as it is being reformed.

7. An arch support fitter device which lends itself to reforming and customizing selective portions of an arch support including releasable means to clamp the arch support to the device, the improvement comprising arch support deforming means carried on the device which is vertically and horizontally movable relative to the arch support to enable force to be applied against the arch support at selective variable angles in customizing and in reforming the arch support to the specification of a foot.
